(57) **CLAIM**

The ornamental design for a raised directional indicator for a fire hose coupling, as shown and described.

DESCRIPTION

FIG. 1 is a perspective view of a first embodiment of the ornamental design.

FIG. 2 is a top view of said first embodiment of the ornamental design.

FIG. 3 is a bottom view of said first embodiment of the ornamental design.

FIG. 4 is a front view of said first embodiment of the ornamental design.

FIG. 5 is a rear view of said first embodiment of the ornamental design.

FIG. 6 is a left view of said first embodiment of the ornamental design.

FIG. 7 is a right view of said first embodiment of the ornamental design.

FIG. 8 is a perspective view of a second embodiment of the ornamental design.

FIG. 9 is a top view of said second embodiment of the ornamental design.

FIG. 10 is a bottom of said second embodiment of the ornamental design.

FIG. 11 is a front view of said second embodiment of the ornamental design.

FIG. 12 is a rear view of said second embodiment of the ornamental design.

FIG. 13 is a left view of said second embodiment of the ornamental design.

FIG. 14 is a right view of said second embodiment of the ornamental design.

FIG. 15 is a perspective view of a third embodiment of the ornamental design.

FIG. 16 is a top view of said third embodiment of the ornamental design.

FIG. 17 is a bottom view of said third embodiment of the ornamental design.

FIG. 18 is a front view of said third embodiment of the ornamental design.

FIG. 19 is a rear view of said third embodiment of the ornamental design.

FIG. 20 is a left view of said third embodiment of the ornamental design; and,

FIG. 21 is a right view- of said third embodiment of the ornamental design.

(Continued)

The broken lines in the drawings are included to show the environment related to the claimed design and form no part of the claimed design.
